FIRETUBE BAFFLE INSERT WITH PROTECTED TIP FOR HEAT EXCHANGERS

Minor Woolfolk Stout, Webster Groves, Mo.

Application November 5, 1947, Serial No. 784,283

7 Claims. (Cl. 110—97)

1.

This invention relates to improvements in accessories for heat exchangers. More particularly this invention relates to an improved accessory that can be used with a heat exchanger to increase the efficiency of operation of that heat exchanger while permitting a reduction in the size of that heat exchanger without a decrease in its capacity.

It is therefore an object of the present invention to provide an improved accessory that can be used with a heat exchanger to increase the efficiency of operation of that heat exchanger while permitting a reduction in the size of that heat exchanger without a decrease in its capacity.

In the operation of heat exchangers, of the type referred to as boilers, it is customary to position a vaporizable liquid in a container or housing and to subject that container or housing to heat. In those instances where the container or housing is heated by the products of combustion of solid, liquid, or gaseous fuels, it has been found advantageous to provide fire tubes that extend through the container or housing and conduct the products of combustion through that container or housing. The fire tubes greatly increase the effective area through which heat can pass from the products of combustion to the vaporizable liquid, and thus they increase the efficiency of operation of the heat exchangers. While the fire tubes do act to increase the efficiency of operation of the heat exchangers, those tubes are not as efficient as they could be because they permit the products of combustion to stratify as they pass through the fire tubes. Such stratification permits the products of combustion, in contact with the fire tubes, to lose their heat and then act as a sheath or layer of relatively cool gas that acts to retard the transfer of heat from the hotter core of the products of combustion to the surfaces of the fire tubes. In such instances, a large proportion of the molecules in the products of combustion do not transfer their heat to the fire tubes, but instead carry most of their heat with them as they pass to the stack or chimney. The heat of such molecules is thus lost since it is dissipated in the atmosphere. Various methods have been proposed and devised to prevent stratification of the products of combustion in fire tubes, and one such method contemplated the formation of fire tubes with grooves that would cause directed flow of the products of combustion through the fire tubes. This method was exceedingly expensive because of the cost of making such tubes; and despite the high cost it failed to break up the hot core of the

2.

products of combustion. Another method contemplated the positioning of lengths of twisted wire cable in the fire tubes to cause directed flow of the products of combustion through those tubes; but that cable merely directed, and did not force, the movement of the products of combustion. While these methods could be of some benefit, in the sense that a directed flow of the products of combustion tends to reduce stratification, those methods are far from satisfactory; since it is necessary to provide a structure that not only breaks up the hot core of the products of combustion, but positively forces those products of combustion against the surfaces of the fire tubes. Such a structure will cause the heated molecules, of the hot core of the products of combustion, to move radially outward until they strike the surfaces of the fire tubes; and it will also cause those molecules to scour those surfaces by constantly replacing the cooled molecules with heated molecules that can transfer their heat to the fire tubes. The radial movement of the molecules breaks the streamline flow of the products of combustion and causes turbulence; and that turbulence will force the products of combustion to intermingle and admix and assist the scouring action. It is therefore an object of the present invention to provide an accessory that positively forces the products of combustion in the fire tubes of a heat exchanger to move radially outward and to scour the surfaces of the fire tubes.

The accessory which is provided by the present invention is preferably a flat piece of metal that has been twisted into the form of a helix. This piece of metal can be positioned within a fire tube of a heat exchanger; and when so positioned it will positively force the products of combustion to change direction and to follow a helical path. While following this path, the molecules of the products of combustion will experience considerable turbulence; and this turbulence will cause recurrent scouring of the surface of the fire tube by the products of combustion. The helical strip of metal not only avoids stratification and an axial flow of the products of combustion, but it forces each of the molecules of the products of combustion to contact and scour the inner surfaces of the fire tube and transfer its heat to that tube. In this way, the helical strip of metal prevents the formation of a relatively cool, heat-retarding sheath of gas adjacent the inner surface of the fire tube, and thus the strip makes it possible for the vaporizable liquid in the container or housing to absorb heat from all, rather than just a few, of the molecules of the products

of combustion. This greatly improves the operating efficiency of the heat exchanger, because it forces the molecules in the products of combustion to transfer most of their heat to the fire tubes, thus reducing the amount of heat that goes up the stack and is lost to the atmosphere. It is therefore an object of the present invention to provide a helical strip of metal which can be positioned within the fire tube of a heat exchanger and can act to force the products of combustion to move radially outward and scour the inner surface of that tube.

To be quite efficient, the helical strip of metal should be quite thin so it does not unduly reduce the available cross section of the fire tube, but a thin strip of metal is not easily positioned within a small diameter tube. However, the helical strip of the present invention can be made quite thin, without detracting from its support, by having that strip rest directly upon the inner surface of the fire tube. The succeeding turns of the helical strip will stiffen that strip considerably; and those portions of the edges of that strip which engage the lower half of the inner surface of the tube will support that strip and hold it in position. While supported in this position, the helical strip of metal will obviate a hot core in the products of combustion; indeed it will force the molecules of those products of combustion to move radially outward and scour the inner surface of the fire tube. It is therefore an object of the present invention to provide a thin helical strip of metal which has a number of complete twists or turns and is made to rest on the inner surface of the fire tube of a heat exchanger.

For extremely high efficiency of operation of the heat exchanger, a tip of insulation should be provided for the leading edge of the strip of metal. This tip performs two important but distinct functions; it isolates the flaming products of combustion from the leading edge of the metal strip and thus keeps that strip from conducting away heat and lowering the combustion temperature, and it becomes red hot and serves to catalytically ignite any unconsumed fuel component in the products of combustion. By keeping the combustion temperature high, and by igniting all of the fuel introduced into the fire tube, the tip of insulation provides even greater efficiency of operation for the heat exchanger. It is therefore an object of the present invention to provide a tip of insulation, for the helical strip of metal, that will keep that strip from reducing the combustion temperature and that will ignite unconsumed fuel components in the products of combustion.

To facilitate the complete combustion of fuel components ignited by the heat from the tip of insulation, the present invention provides sufficient air to support that combustion. While it is important to provide sufficient amounts of air to assure complete combustion of all the fuel used to heat the material in the heat exchanger, it is also important to avoid excessive amounts of air, because excessive amounts of air would reduce the combustion temperature. The present invention provides sufficient air for combustion but avoids reductions in combustion temperatures by limiting the amount of air used in burning the fuel. It is, therefore, an object of the present invention to limit the amount of air used to support the combustion of fuel.

Other and further objects and advantages of the present invention should become apparent

from an examination of the drawing and accompanying description.

In the drawing and accompanying description a preferred embodiment of the present invention is shown and described, but it is to be understood that the drawing and accompanying description are for the purposes of illustration only and do not limit the invention and that the invention will be defined by the appended claims.

In the drawing, Fig. 1 is a side elevational view of a helical strip of metal that is made in accordance with the principles and teachings of the present invention and is provided with a tip of insulation,

15 Fig. 2 is a plan view of the helical strip of Fig. 1, and

Fig. 3 is a partially sectioned side view through a heat exchanger, of the type referred to as boilers; and it not only shows the position of the 20 helical strips in the fire tubes but it also shows the spacing of the fuel and air nozzles from the ends of those fire tubes.

Referring to the drawing in detail, the numeral 10 denotes an elongated strip of metal. This strip is made from a metal which has a melting point greater than the combustion temperature of the fuel; one such metal being steel. A rust-resistant steel, such as stainless steel, is preferred because of its long life; but cold rolled band steel is also usable, and in fact strips of the latter type of steel have been in use for many months. Those strips have become rusty but they still perform their intended function; moreover, the rust seems to assist heat transfer by further increasing turbulence. The strip 10 may be rolled from a bar or it may be cut from a sheet; but however formed, it is then twisted beyond its elastic limit until it assumes a helical configuration. An opening 11 is provided in the trailing end of strip 40 10, and that opening makes it possible to hold the strip 10 extended while it is being twisted; thus making it possible to secure a very small pitch for the helix of the finished strip. Twisting the strip 10 beyond its elastic limit enables 45 that strip to retain its helical configuration despite repeated heating and cooling cycles. The helical configuration is preferably such that the strip 10 has several complete turns or twists intermediate its ends; for the greater the number 50 of such twists, the more effective the scouring action will be. The strip 10 is made quite long; and in fact it is preferably made so its twisted length is just slightly less than the length of the fire tube of the heat exchanger. The strip 10 is 55 made wide enough so it divides the space in a fire tube into two separate parts, but it is made narrow enough to facilitate its forced insertion into the fire tube. A long wire and hook are used to pull the strip into position, the hook fitting 60 into the opening 11 in the trailing end of strip 10. Where the helical strip 10 is made in this manner and is positioned within the fire tube of a heat exchanger, products of combustion introduced 65 into that fire tube will initially and positively be divided into two separate masses. Being of smaller volume, the two masses will be easier to direct than would the original large mass; and those two masses will repeatedly be forced to move radially outward as they pass through the 70 fire tube because the strip 10 blocks stream line, axial movement. As the two masses change direction, they experience considerable turbulence and an appreciable reduction in velocity. The turbulence of the masses eliminates stratification 75 and enables most of the molecules of the products

of combustion to contact the surface of the fire tube and transfer their heat to that tube; and the reduction in the velocity of the products of combustion increases the effective time during which the products of combustion can transfer their heat to the fire tube. The combined effect of the turbulence and the reduction in velocity is to reduce the required length of fire tube for a given efficiency of combustion or a given heat-exchanging capacity; thus reducing the size and cost of the heat exchanger.

The helical strip of metal can be positioned in the fire tube of a boiler; and when so positioned it will provide the desired radial movement and scouring action of the products of combustion, and it will reduce the velocity of those products of combustion. Where desired, however, that strip of metal can have its leading end provided with a tip of insulation. This tip may be formed from two sheets 12 of insulation which have their trailing ends cut, or otherwise formed, to provide a recess in which the leading end of the helical strip 10 can be positioned. The sheets 12 of insulation must be capable of withstanding temperatures above two thousand (2000) degrees Fahrenheit, and they must have sufficient structural strength to withstand handling during shipment and installation. One material that has been found to be very effective is a mixture of asbestos fibers and Portland cement which is prepared and sold by the Ruberoid Company under the designation "Stone Wall." That material has a composition of fifteen percent (15%) asbestos fibers and eighty-five percent (85%) Portland cement, and it is quite sturdy. The trailing ends of the sheets 12 have openings therein, and those openings are in register with each other and in register with an opening in the leading end of the helical strip 10. These openings receive a rivet 14 which secures the sheets 12 to the strip 10; and while the rivet 14 may be made of several metals, copper is preferred. The expansion of the copper rivet 14, when heated, is sufficient to compensate for any expansion of the sheets 12 and strip 10; and thus the sheets 12 will not be unduly compressed and crushed during heating and cooling. The leading ends of the sheets 12 of insulation also have openings, and those openings receive the rivet 16. This rivet also is preferably of copper, and it holds the abutting surfaces of the sheets 12 so close together that little if any of the products of combustion introduced into the fire tube can pass to and engage the leading end of the helical strip 10. Consequently, the metal strip 10 cannot conduct away heat from the flaming products of combustion entering the fire tube and cannot reduce combustion temperatures; instead the heat of the flaming products of combustion will be held by the tip of insulation and will serve to ignite any unconsumed fuel in those products of combustion. By preventing reductions in combustion temperatures and by catalytically igniting unconsumed fuel components, the tip of insulation further increases the efficiency of operation of the heat exchanger.

Sufficient air must be supplied to support both the initial and secondary combustion of the fuel. In the construction shown in the drawing, part of the air is admixed with fuel and is expelled through nozzles, while the rest of the air is drawn into the fire tubes by the jet action of the flaming products of combustion. By regulating the diameter of the fire tubes, the pressure on the mixture of air and fuel issuing from the nozzles,

and the spacing between the nozzles and the fire tubes, it is possible to attain enough secondary air to support the complete combustion of fuel ignited by the tip of insulation; while avoiding an excess of air which would lower the combustion temperature. In some instances where it is desirable to avoid reliance on secondary air, as where that air is dirty or has undesirable components, the nozzles can be placed within the fire tubes and the primary air increased to the point where it can assure complete combustion of all fuel introduced into the fire tubes.

In Fig. 3, a portion of a heat exchanger is shown, and that heat exchanger has a plurality of fire tubes 18 which are disposed in parallel relation to each other. The fire tubes 18 are supported at each end by tube sheets 20, only one of which is shown; and the connection between the tube sheets 20 and the fire tubes 18 is made water-tight by rolling or welding the tubes 18 into place. A series of pipes 22 are disposed in register with the ends of the fire tubes 18; and each of the pipes 22 is provided with a nozzle 24. The nozzles 24 have restricted orifices, and they may be made by drilling openings of the desired diameters in rods and then pressing the drilled rods into the exit ends of the pipes 22. The exit ends of the nozzles 24 are preferably spaced inwardly about one-half (1/2) inch from the exit ends of the pipes 22. A number of tubes 26 extend transversely across the end of the heat exchanger immediately below the aligned pipes 22; and those tubes have openings in register with the pipes 22. By connecting pipes 26 to a source of inflammable gas or vapor, it is possible to make tubes 26 serve as automatic pilot lights for the main nozzles 24 of the heat exchanger. The mixture of fuel and air issuing from nozzles 24 will be ignited by the pilot lights and will pass into the ends of fire tubes 18. The strips 10 of metal in those tubes will be spaced inwardly from the ends of those tubes; and the tips of the flames issuing from the nozzles 24 should impinge upon and strike the tips of insulation on the strips 10 of metal, overlapping the leading ends of those tips about one-half (1/2) inch.

In the operation of the heat exchanger, that is partially shown in Fig. 3, a mixture of air and inflammable gas or vapor is introduced into the pipes 22 under pressure and is caused to issue from the nozzles 24 in streams. The streams will be ignited by the pilot lights from tubes 26, and they will form flames that extend into the fire tubes 18 and impinge upon the insulation tips on the ends of the helical strips 10. As previously indicated, the flames and the products of combustion in each tube 18 will then be divided into two masses; one passing to one side of the helical strip 10 and the other passing to the other side of that strip. Because of their inertia, the flames and products of combustion will tend to move axially of the tubes 18 in streams, but as they move in that direction they will strike the helical strips 10 which positively prevent uninterrupted linear axial movement of the flames and products of combustion in streams. The engagement between the strips 10 and the products of combustion positively forces the products of combustion to move radially outward and to scour the inner surfaces of the fire tubes, and that engagement also causes a considerable reduction in the velocity of flow of those products of combustion.

Operation of heat exchangers of the type shown in Fig. 3 proves that the use of helical strips 10 in the fire tubes 18 causes decreases in the velocity of the products of combustion of as much as forty percent (40%). Such decreases are of tremendous value since they increase the time during which any particular molecule in the products of combustion remains within a fire tube, thus increasing the total amount of heat which that molecule transfers to that tube. The decrease in velocity of the products of combustion cooperates with the ignition of unconsumed fuel, when it strikes the red hot tip of insulation, to make possible reductions of as much as fifty percent (50%) in the length of fire tube travel for a given combustion efficiency or given heat exchanging capacity. Such reduction greatly reduce the dimensions and costs of the heat exchangers.

An impressive illustration of the effectiveness of the helical strips 10 can be made by operating a heat exchanger with and without the helical strips 10. Where the strips 10 are removed from the fire tubes, the stack temperatures will be in the range of from seven hundred (700) to eight hundred (800) degrees Fahrenheit, but where the strips 10 are positioned in the fire tubes the stack temperatures will be as low as four hundred (400) to five hundred (500) degrees Fahrenheit. The strips 10 of metal thus cause the products of combustion to yield an additional three hundred (300) degrees Fahrenheit of their heat to the fire tubes, thus showing conclusively the improved heat transferring ability of the strips 10. Moreover, the operation of boilers equipped with helical strips 10 has shown that the strips 10 make it possible to increase the unit overall heat transfer rate of the fire tubes as much as seventy-five (75) to eighty (80) percent.

In one instance, a one pass heat exchanger was built in the manner indicated in Fig. 3, and it was equipped with helical strips as shown in Fig. 3. The combustion temperature of the gas used with that heat exchanger was approximately two thousand (2000) degrees Fahrenheit, the temperature of the water in the heat exchanger was two hundred and thirty-five (235) degrees Fahrenheit, and the stack temperature was only three hundred and five (305) degrees Fahrenheit; and when a sample of stack gas was analyzed it was found to contain nine percent (9%) carbon dioxide (CO₂), three percent (3%) oxygen (O₂), and no carbon monoxide (CO). This is an amazing record since the stack temperature is about seventeen hundred (1700) degrees below the combustion temperature of the gas used, and it is only seventy (70) degrees above the temperature of the water being heated. Moreover, the high percentage of carbon dioxide (CO₂), the low percentage of oxygen (O₂), and the complete absence of carbon monoxide (CO) in the stack gases shows that all of the fuel was consumed without the use of excessive amounts of air that could reduce combustion temperatures. Reference to the proper Nomograph of the American Gas Association shows that this heat exchanger has an American Gas Association efficiency of eighty-four percent (84%); an efficiency that one pass heat exchangers don't ordinarily have, and that two pass and three pass heat exchangers rarely attain despite their added cost. In all respects, the helical strips 10 greatly increase the efficiency and value of the heat exchangers in which they are used; and in comparison with the results which they make possible, their cost is trivial.

The side edges of the strips 10 rest upon the surfaces of the fire tubes 18, and thus those side edges enable the strips to intercept all of the products of combustion and force them to scour the inner surfaces of the fire tubes 18. The leading ends of the strips 10 are preferably spaced from the nozzles 24 a distance sufficient to permit the flames to impinge upon the tips of insulation. This keeps those tips red hot, thus enabling them to ignite unconsumed fuel components in the products of combustion. The air to support the secondary combustion of the fuel, as where part of the gas has been converted to carbon monoxide (CO) and must be converted to carbon dioxide (CO₂), may be provided in the form of secondary air, as shown in Fig. 3, or it may be provided in the form of excess primary air. In either case, however, it will be found that the amount of air required, where the strips 10 are used, can be regulated more closely than when those strips are not used. This is partially due to the reduced velocity of the products of combustion, it is partially due to the scouring action of the products of combustion, and it is also partially due to the completeness of combustion effected by the tips of insulation; and that close regulation of air avoids the use of such excesses of air as would lower the combustion temperature.

Whereas a preferred embodiment of the present invention has been shown and described in the drawing and accompanying description it should be obvious to those skilled in the art that various changes may be made in the form of the invention without affecting the scope thereof.

35 What I claim is:

1. In a heat exchanger which comprises a fire tube, a tube sheet to support an end of said fire tube, a burner nozzle in register with and directed into said end of said fire tube, and a pipe to conduct fluid fuel to said nozzle for burning in said fire tube, the improvement that comprises a strip of metal extending longitudinally within said fire tube, said strip of metal having a tip of low heat conductive refractory material thereon in register with and opposite to said burner nozzle, said strip being substantially as wide as the inner diameter of said fire tube and extending rearwardly from said tip and away from said burner nozzle, said strip and said tip thereon being arranged diametrically of said fire tube and being in the path of products of combustion in said tube and coating with said tube to divide the products of combustion into a plurality of masses, said tip igniting unconsumed fuel components in the products of combustion from the fuel directed into said fire tube by said burner nozzle, said tip comprising flat, thin sheets of low heat conductive refractory material that are held in coplanar, abutting relation with, and that overlie, the leading end of said strip of metal to protect said one end of said strip of metal.
2. In a heat exchanger which comprises a fire tube, a tube sheet to support an end of said fire tube, a burner nozzle in register with and directed into said end of said fire tube, and a pipe to conduct fluid fuel to said nozzle for burning in said fire tube, the improvement that comprises a strip of metal extending longitudinally within said fire tube and being substantially as wide as the inner diameter of said fire tube, said strip of metal having a tip of low heat conductive refractory material thereon in register with and opposite to said burner nozzle to ignite unconsumed fuel components in the products of combustion from the fuel directed into said fire tube by said burner

nozzle, said tip comprising flat, thin sheets of low heat conductive refractory material that are held in coplanar, abutting relation with, and that overlie, one end of said strip of metal to protect said one end of said strip of metal, said tip and strip being arranged in substantially bisecting relationship of said fire tube to force the products of combustion within said fire tube to divide into two masses and said strip being twisted along its length to force those masses to scour the inner surface of said fire tube.

3. In a heat exchanger which comprises a fire tube, a tube sheet to support an end of said fire tube, a burner nozzle in register with and directed into said end of said fire tube, and a pipe to conduct fluid to said nozzle for burning in said fire tube, the improvement that comprises a strip of metal extending longitudinally within said fire tube, said strip of metal having a tip of low heat conductive refractory material thereon in register with and opposite to said burner nozzle to ignite unconsumed fuel components in the products of combustion from the fuel directed into said fire tube by said burner nozzle, said tip comprising elongated flat, thin sheets of low heat conductive refractory material, said sheets of refractory material having the confronting surfaces at the rear ends thereof cut away, said sheets of refractory material being disposable in abutting co-planar relation so the cut-away confronting surfaces at the ends thereof form a recess, said sheets of refractory material being dimensioned so the recess formed by the cut-away confronting surfaces thereof receives and telescopes over the said one end of said strip of metal, the forward ends of said sheets of refractory material projecting ahead of said one end of said strip of metal to protect the edge of said one end of said strip of metal, said strip being substantially as wide as the inner diameter of said fire tube and extending diametrically of said fire tube.

4. In a heat exchanger which comprises a fire tube, a tube sheet to support an end of said fire tube, a burner nozzle in register with and directed into said end of said fire tube, and a pipe to conduct fluid fuel to said nozzle for burning in said fire tube, the improvement that comprises a strip of metal extending longitudinally within said fire tube, said strip of metal having a tip of low heat conductive refractory material thereon in register with and opposite to said burner nozzle to catalytically ignite unconsumed fuel components in the products of combustion from the fuel directed into said fire tube by said burner nozzle, said tip comprising elongated, flat, thin sheets of low heat conductive refractory material, said sheets of refractory material having the confronting surfaces at the rear ends thereof cut-away, said sheets of refractory material being disposable in abutting co-planar relation so the cut-away confronting surfaces at the ends thereof form a recess, said sheets of refractory material being dimensioned so the recess formed by the cut-away confronting surfaces thereof receives and telescopes over the said one end of said strip of metal, the forward ends of said sheets of refractory material projecting ahead of, and overlying, said one end of said strip of metal to protect the edge of said one end of said strip of metal, said strip having a plurality of turns or twists intermediate its ends.

5. An axially extended helicoidal strip of metal

that is adapted to be positioned within a fire tube of a heat exchanger, said strip having curved, axially extended, helicoidal surfaces, said strip being adapted to be arranged diametrically of said fire tube to force the products of combustion within said tube to change direction from normal axial flow and to experience turbulence, and a tip of low heat conductive refractory material on one end of said strip of metal, said tip comprising flat, thin sheets of low heat conductive refractory material that are held in coplanar, abutting relation with, and that overlie, one end of said strip of metal to protect said one end of said strip of metal, said tip being adapted to be heated to incandescence to catalytically ignite unconsumed fuel components in the products of combustion adjacent said tip.

6. An axially extended helicoidal strip of metal that is adapted to be positioned within the fire tube of a heat exchanger, said strip being adapted to bisect said fire tube and having curved, axially extended, helicoidal surfaces adapted to force the products of combustion within said tube to change direction from normal axial flow and to experience turbulence, and a tip of low heat conductive refractory material that comprises thin sheets of low heat conductive refractory material which are attached to and supported on one end of said strip of metal, said tip enclosing the end of said strip of metal and extending ahead of said end of said strip of metal.

7. A formed strip of metal that is adapted to be positioned within the fire tube of a heat exchanger, said strip being adapted to bisect said fire tube and having twisted, axially extended curved surfaces adapted to force the products of combustion within said tube to change direction from normal axial flow and to experience turbulence, and a tip of low heat conductive refractory material on one end of said strip of metal, said tip comprising elongated, flat, thin sheets of low heat conductive refractory material, said sheets of refractory material having the confronting surfaces at the rear ends thereof cut-away, said sheets of refractory material being disposable in abutting co-planar relation so the cut-away confronting surfaces at the ends thereof form a recess, said sheets of refractory material being dimensioned so the recess formed by the cut-away confronting surfaces thereof receives and telescopes over the said one end of said strip of metal, the forward ends of said sheets of refractory material projecting ahead of and overlying said one end of said strip of metal to protect the edge of said one end of said strip of metal, said tip of refractory material being adapted to keep said strip of metal from conducting away the heat of said products of combustion.
